UNITED STATES PATENT OFFICE.

EDWARD B. CALL, OF PEORIA, ILLINOIS.

DENTAL BRIDGE-WORK.

SPECIFICATION forming part of Letters Patent No. 445,309, dated January 27, 1891.

Application filed January 24, 1890. Serial No. 337,971. (No model.)

To all whom it may concern:

Be it known that I, EDWARD B. CALL, a citizen of the United States, residing at Peoria, in the county of Peoria and State of Illinois, have 5 invented certain new and useful Improvements in Dental Bridge-Work; and I do hereby declare the following to be a full, clear, and exact description of the invention, such as will enable others skilled in the art to which 10 it appertains to make and use the same.

This invention relates to improved methods in the art of dentistry, as well as to improved devices for use in that art.

I refer to the accompanying drawings, and 15 by their aid will describe my invention.

Figure 1 shows a longitudinal section of an artificial tooth having holes pierced through it from the palatal to the labial sides. The holes are countersunk on the labial side, as 20 shown at A' A'. Fig. 2 is a cross-section of a tube B, having a screw-thread cut upon its interior surface, and also showing the cross-section of a bolt having a screw-thread fitting the interior of said tube. This tube, as well 25 as the bolt, is provided with a head, which for convenience I make square, and also having a shoulder under the head shown at B' B', and designed to fit the countersink in the tooth before mentioned. The bolt is shown in this 30 figure at C, Fig. 2. Fig. 3 is a bridge, as that term is used in the dental art.

D D are natural teeth.

F is a plate, preferably of metal, rigidly attached to the natural teeth, as shown.

35 E E are artificial teeth attached to said plate in the ordinary way.

D' shows a part of the plate F, from which an artificial tooth has been broken off. G is an artificial tooth attached to said plate by 40 means of my device. The bolt is shown smooth upon the outside, having the appearance of a filling.

My device is adapted especially for repairing bridge-work, as has been described. It 45 may be used, however, in any place where it is designed to replace an artificial tooth casually broken from either a plate or a bridge or pivot, and obviates the necessity of injuring such plate or destroying the bridge when

attached permanently to the teeth, and the 50 operation may be performed without pain to the patient.

I describe the use of my invention as follows: Where it is designed to supply an artificial tooth broken from a bridge, as shown 55 and described, I make an artificial tooth of any ordinary material, preferably of plastic material vitrified by fire. Through this I pierce one or more holes, as shown at Fig. 1. This tooth I fit to its place upon the bridge, 60 then drill holes through the plate corresponding to the holes in the tooth. Through these holes, extending from the palatal side of the plate to the labial side of the tooth, I insert the bolt, or preferably the tube shown at Fig. 65 2, with its bolt as shown at C, Fig. 2, and by means of the screw draw the tooth closely to the plate. I then cut off the head of the bolt leaving the shoulder in the countersink which I polish and finish as an ordinary filling. 70 This same process may be observed in a re-attachment or replacing a tooth broken from a removable plate.

Instead of the tube with its interior screw and bolt fitted therein, I have in some cases 75 made use of a simple bolt having an ordinary nut thereon; but I regard the tube as preferable in all cases where I have been called to use it.

Having thus described my invention, what I 80 claim as mine, and desire to secure by Letters Patent, is—

For replacing artificial teeth either upon bridge-plate or pivot-work, an artificial tooth having one or more holes pierced through it 85 from the palatal to the labial side, countersunk on the labial side, held in place by a tube fitted with a screw upon its interior surface, and having a bolt fitted to screw into the said tube, all acting together in the manner and 90 for the purpose specified.

In testimony whereof I affix my signature in presence of two witnesses.

EDWARD B. CALL.
